COMBINED FLOWER HOLDER AND CANDY SUPPORT

Saul Klayman, Mattapan, Mass., assignor to Kandy-pak, Inc., Roslindale, Mass., a corporation of Massachusetts

Filed Nov. 14, 1967, Ser. No. 9,398

Term of patent 14 years

(Cl. D44—10)

FIG. 1

FIG. 2

The broken line showing of candy in FIGURE 1 is for illustrative purposes only.

I claim:

The ornamental design for a combined flower holder and candy support, substantially as shown and described.
